ATTORNEY

UNITED STATES PATENT OFFICE.

JOHN B. TEESDALE, OF GRAND RAPIDS, MICHIGAN.

PUMP.

Application filed February 23, 1923. Serial No. 620,759.

The present invention relates to pumps; and its object is, generally, to provide a rotary pump improved in certain respects hereinafter appearing, and more particularly to provide priming means for pumps of this character.

This and any other objects hereinafter appearing are attained by, and the invention finds preferable embodiment in, the structure hereinafter particularly described and illustrated by the accompanying drawings, in which:—

Figure 1 is a transaxial sectional view of a rotary pump;

Figure 2 is an axial sectional view thereof taken on line 2—2 of Figure 1;

Figure 3 is an enlarged detail transaxial view of parts of the same, showing a modified construction; and

Figure 4 is a detail transaxial view of certain parts, showing another modified construction.

In the drawings, a rotary pump is shown, comprising a body 1 having a cross-sectionally circular chamber 2 horizontally disposed axially, a passage 3 having an intake 5 and a port 4 to the lower portion of said chamber, the pump comprising also a cross-sectionally circular piston 11 in, and diametrically smaller than, the chamber and in axially parallel relation therewith. Means are provided for travelling this piston about an axis parallelly offset from the piston's axis, i. e., in such manner that the axis of the piston moves in such travel in a circle whose center is the axis of the chamber, the pumped liquid being thus forced circularly in the chamber by the snugly fitting relation of successive portions of the piston's periphery with the chamber's circular wall.

In the construction illustrated, said means comprise the driving shaft 13 coaxial with the chamber and carrying the eccentric cam member 12 therein on which cam member the piston is turnably mounted. A closure 7 extends transversely of the passage 3 and through the port 4, in spaced relation from said port's sides, and is fittingly connected swingably to the body 1 at

8 and to the piston 11 at 10. This port 4 is at a lower level than the bottom of the passage 3 toward its intake 5, so that when the pump is not operating, a sufficient amount of liquid for priming its next operation 55 may be retained in the port 4 at the intake side thereof. This priming operation is insured by closure's middle portion being depressed below its connections 8 and 10, thus forming a pocket for holding the priming 60 liquid.

It will be seen that the rotation of the driving shaft 13 in the direction of the arrow in Figure 1 draws the liquid into the chamber 2 through the port 4 at the side 65 thereof which is toward the intake 5 and expels the liquid through said port as its opposite side which is toward the vent 6 of the pump.

In the modified construction shown in 70 Figure 3, the closure 7¹ has a projection 20 adapted to close the space 21 between the piston 11¹ and the inner surface of the chamber at the port 4¹ when the piston moves away therefrom.

In the further modified construction illustrated in Figure 4, a packing sheet 22 is applied to the piston's perimeter and held in grooves 23 therein by binding strips 24.

I claim:

1. In a structure of the character described: a body having a cross-sectionally circular chamber horizontally disposed axially, and a passage having an intake and a port to the lower portion of the chamber at a lower level than the bottom of the passage toward its intake; a cross-sectionally circular piston within, and diametrically smaller than, the chamber, in axially-parallel relation therewith; means for travelling the piston about an axis parallelly offset from its axis; a closure extending transversely of the passage and through, and in spaced relation from the sides of, the port and fittingly connected to the piston and the body.

2. In a structure of the character described: a body having a cross-sectionally circular chamber horizontally disposed axially, and a passage having an intake and a

port to the lower portion of the chamber; a cross-sectionally circular piston within, and diametrically smaller than, the chamber, in axially-parallel relation therewith; ⁵ means for travelling the piston about an axis parallelly offset from its axis; a closure extending transversely of the passage and through, and in spaced relation from

the sides of, the port, and fittingly connected to the piston and to the body and having ¹⁰ a portion intermediate, and depressed below, such connections.

In testimony whereof I affix my signature.

JOHN B. TEESDALE.
